UNITED STATES PATENT OFFICE.

AUSTIN R. DODGE, OF SCHENECTADY, NEW YORK, ASSIGNOR TO GENERAL ELECTRIC COMPANY, A CORPORATION OF NEW YORK.

FEED-WATER REGULATOR.

1,154,592.

Specification of Letters Patent. Patented Sept. 21, 1915.

Application filed December 20, 1912. Serial No. 737,868.

To all whom it may concern:

Be it known that I, AUSTIN R. DODGE, a citizen of the United States, residing at Schenectady, county of Schenectady, State of New York, have invented certain new and useful Improvements in Feed-Water Regulators, of which the following is a specification.

This invention has relation to steam boilers and its object is to provide an improved system of feeding water to such boilers, whereby the amount of water supplied will depend not only upon the variation of the water level in said boilers or boiler but also upon the demand for steam; a greater supply being provided when the amount of steam drawn off is increased. To this end I equip the boiler with a means sensitive to changes in the rate of flow of the steam leaving the boiler, and arrange this means to cooperate with a means sensitive to changes in water level, both of said means having control of the admission of water to the boiler, either directly or indirectly, as may be desired.

The accompanying drawing is an end elevation of a pair of boilers equipped with the invention, the mechanism having a direct control of the water supply.

Two horizontal boilers 1, 2 are shown delivering steam into a header 3 from which the main 4 runs to the point of steam consumption. A pipe 5 supplies water to said boilers, the feed pump and the connection to said boilers being omitted for the sake of simplicity in the drawing. A valve 6 controls the feed pipe 5, and the stem 7 of said valve is pivotally attached to one end of a floating lever 8 whose other end is pivotally connected to a hollow head 9 in which is inserted one end of an inclined tube 10, of material expansible by heat. The other and lower end of said tube is fixed in a support 11 and connects with the passage 11^a therein which in turn is connected with a small chamber 12 standing at about the same level as the head 9. Surrounding the tube 10 is a cooling device, such for example as the spiral fin 13, which affords a large radiating surface.

In the steam main 4 is an impact nozzle 14 which is connected by a pipe 15 with the hollow head 9, and is preferably provided with a means for permitting said pipe to expand and contract without affecting its

position, such for example as the horizontal U bend 16. The chamber 12 is also connected with the steam main by the pipe 17. The entering end of pipe 17 forms the trailing or low pressure side of a device which creates a pressure difference which bears a definite relation to the rate of flow of steam through the main, the impact nozzle forming the leading or high pressure side thereof. In other words, the pipe 15, expansible tube 10, and pipe 17 form in substance a U-tube having its two ends connected into the steam main through an impact nozzle and an orifice. When steam is flowing through the main there will be set up a difference in pressure between the two ends of the U-tube, which difference is proportional to the rate of flow. When in operation, steam enters the tube 10 through the nozzle 14 and condenses therein tending to fill the same with water. The difference in pressure on the two ends of the tube, set up by the flow of steam, will tend to force this water out through the pipe 17 against the static head therein, and it will assume a level in the tube 10 due to this pressure difference which is proportional to the rate of flow. Of course steam will be continuously condensing to a greater or less extent in the tube 10 and the excess of water thus formed will be spilled out through the end of the pipe 17 over into the main. The pressure of the steam due to its velocity as it makes impact upon the nozzle will force said water to the lower portion of said tube and up into the chamber 12. The level of this body of water in the tube will vary with said pressure and consequently with the rate of flow of the steam through the main 4. More or less of the tube will thus be exposed to the temperature of the live steam, which will cause a greater or less longitudinal expansion of the tube, as the case may be, and said expansion will vary with the rate of steam flow. This will produce a movement of the head 9 and will actuate the floating lever 8. In order that this movement may open or close the valve 6 and thus regulate the amount of water feeding into the boilers, a fulcrum is provided for said lever at a point intermediate between the stem 7 and the other end of the lever. To afford perfect freedom of movement, the lever is slotted at 18 for engagement by one arm of a bent lever 19 which is fulcrumed on an adjustable support, such as

the rock arm 20 pivoted at 21 and connected to a rod 22 which passes through a standard, such as the base of the hollow head 11, and is provided with a screw threaded end 23 carrying an adjusting nut 24. The other arm of the bent lever 19 is connected to a hollow head 25 which supports the upper end of an inclined expansion tube 26 whose lower end is received in a chamber 27 in the base of the head 11. This chamber is connected by a pipe 28 with the water space of the boilers, while the head 25 is connected by a pipe 29 with an upright receptacle 30 connected at its bottom with the water space 15 and at its top with the steam space of said boilers. The point of attachment of the pipe 29 is coincident with the center gage cock 31.

The operation is as follows: When by evaporation the water in the boilers drops below the center gage of the water column in the receptacle 30 and steam from the upper half of said receptacle passes through the pipe 29 to the expansion tube 26, said tube becomes expanded by the heat and causes the bent lever 19 to actuate the floating lever 8, which fulcrums on its upper end and pulls open the valve 6 to admit water to the boilers. With the rise of the water line, the free opening at the center gage becomes sealed and the steam supply to the expansion tube 26 is cut off. The tube, deprived of the heat required to maintain it expanded, contracts, and acts through the levers 19 and 8 to close the valve 6 again. This mode of regulating the feed water is not of my invention, being already in well-known use. The parts which I have added are those first described above, whereby the flow of steam through the main 4 may regulate the feed water. The operation of these parts is as follows: The tube 10 is always in a heated condition, but the amount of its expansion varies with the length of the portion exposed 45 to the live steam entering through the pipe 15; this length varying with the velocity of the steam flow and consequently the pressure set up in said tube upon the water of condensation therein, whose level will therefore vary with said pressure. When the steam flow increases, the water will be forced lower down in said tube, and a longer portion will be exposed to the steam, thereby causing the tube to expand more lengthwise. 50 This movement is communicated to the floating lever 8 which will fulcrum on the bent lever 19 and pull the valve 6 open to admit more water to make up for the faster rate of evaporation, due to the increased demand upon the boilers. When the demand slacks off, a reverse operation takes place. In case the demand for steam should be so great that the expansion tube 10 did not respond quickly enough to keep the water level up 55 to the center gage line, and it should drop

below that line, then the expansion tube 26 will also come into play and add its effect to produce a wider opening of the valve 6. The two devices thus supplement each other in case of need, while they act independently 70 when the conditions are such that either one or the other becomes necessary to meet those conditions.

In accordance with the provisions of the patent statutes, I have described the principle of operation of my invention, together with the apparatus which I now consider to represent the best embodiment thereof; but I desire to have it understood that the apparatus shown is only illustrative, and that 80 the invention can be carried out by other means.

What I claim as new and desire to secure by Letters Patent of the United States, is:—

1. The combination with a steam boiler and a steam main connected therewith, of a feed water pipe for the boiler, a valve controlling the flow of water therethrough, means responsive to the level of the water in the boiler for regulating said valve, and means responsive to the rate of flow of steam from the boiler for also regulating said valve, said last named means comprising an expansible tube having its opposite ends connected to the main through a device which 90 creates a pressure difference which is proportional to the rate of flow of steam therethrough.

2. The combination with a steam boiler and a steam main connected therewith, of a feed water pipe for the boiler, means for regulating the flow of water through said pipe, and means responsive to the rate of flow of steam through the main for controlling said regulating means, comprising a 100 tube of expansible material, pipes connecting the ends of said tube with the main, and means therein associated with the pipes for creating a pressure difference which bears a definite relation to the rate of flow of steam 105 through the main.

3. The combination with a steam boiler and a steam main connected therewith, of a feed water pipe therefor, a valve controlling the flow of water therethrough, a floating 115 lever connected to said valve, an expansion tube responsive to variations in the water level in said boiler connected to said lever, and a second expansion tube also connected to said lever, said second tube being inclined 120 and having its two ends connected into the main through a device which creates a pressure difference on the tube proportional to the rate of flow of steam through the main whereby said tube will tend to fill with water 125 of condensation and will be exposed to the temperature of the steam to a greater or less extent according to the rate of flow.

4. The combination with a steam boiler and a steam main connected therewith, of a 130

feed water pipe therefor, a valve controlling the flow of water through the same, an inclined tube of expansible material connected to said valve, an impact nozzle in the steam main connected with the upper end of said tube, and a pipe connecting the lower end of said tube with said main whereby said tube will tend to fill with water of condensation,

the level of which will depend upon the rate of flow of steam through the main. 10

In witness whereof, I have hereunto set my hand this 19th day of December, 1912.

AUSTIN R. DODGE.
